[57] **CLAIM**

The ornamental design for a mounting clip for conveyor system elements, as shown and described.

DESCRIPTION

FIG. 1 is an isometric view of a mounting clip for conveyor system elements, embodying my new design;

FIG. 2 is a top plan view thereof;

FIG. 3 is a side elevation showing the side not shown in FIG. 1;

FIG. 4 is an end elevation showing either end thereof;

FIG. 5 is a bottom plan view thereof;

FIG. 6 is an isometric view corresponding to FIG. 1 but showing a second embodiment;

FIG. 7 is a view corresponding to FIG. 2 but showing such second embodiment;

FIG. 8 is a view corresponding to FIG. 3 but showing either side of such second embodiment;

FIG. 9 is a view corresponding to FIG. 4 but showing either end of such second embodiment; and,

FIG. 10 is a view corresponding to FIG. 5 but showing the bottom of such second embodiment.

The first and second embodiments are identical to each other except that the second embodiment has projecting spacer pins.

FIG. 1.FIG. 2.FIG. 4.FIG. 3.FIG. 5.

FIG. 6.FIG. 7.FIG. 8.FIG. 9.FIG. 10.
